JULIEN PIETERS, OF PARIS, FRANCE

VERTICAL DISTILLATION RETORT

Application filed March 20, 1928, Serial No. 283,168, and in France March 30, 1927.

The present invention relates to vertical continuous distillation retorts for the distillation of all combustible materials, such as coal, lignite, peat, bituminous shales and the like, of the type in which the longitudinal walls of the distillation chamber are constituted by hollow bricks or tubular elements made of refractory material, of prismatic shape, which, by their superposition and fitting together, form continuous vertical flues for the passage of the gases serving for the heating of said distillation chamber. According to my present invention, there is provided, along the major axis of the oblong cavity of each of the said tubular elements, in the heating zone proper of the distillation chamber, a separate brick extending for a small part of the height of the tubular element, and forming a partition parallel to the longitudinal walls of the said oblong cavity, in combination with means for supporting said brick.

This partition thus reduces the passageway for the flames and combustion gases, causing a thorough mingling of the latter and ensures a better heat transmission to the longitudinal walls of the distillation chamber.

The use of a separate brick of this kind allows the accurate regulation of the passageway of the gases, in order thus to graduate the resistance to their flow and the impact of the gases upon each point of the heating of the distillation chamber.

The accompanying drawings represent by way of example a form of carrying out the object of the invention.

Figure 1 is a view in vertical section, partly in external view, along the broken line 1—1 of Figure 2, the right hand half corresponding to a vertical axial section through a distillation chamber, and the left hand half corresponding to a vertical axial section through a heating pier.

Figures 2 and 3 are views in transverse horizontal section along the line 2—2 and the line 3—3 of Figure 1, respectively, on a larger scale.

Figure 4 is a view in vertical section, at right angles with relation to that of Figure

1, that is to say along the broken line 4—4—4 of Figure 3.

Figures 5 and 6, 7 and 8, 9 and 10, 11 and 12 are respectively a plan and a longitudinal, axial section of elements of different types utilized in the construction of the distillation chamber.

As represented in Figures 1 and 2, the distillation chambers *a* are delimited, upon their long sides, by refractory members or elements *b* of relatively small dimensions; these elements *b* of rectangular section (Figures 5 and 6 and Figures 7 and 8) comprise a central tubular cavity or hollow *b*¹ of oblong shape; there exist two types of these elements *b*, one (Figures 5 and 6) having a lateral rib *b*² and the other (Figures 7 and 8) having lateral grooves *b*³ in such a way as to allow the fitting together of the juxtaposed elements in the direction of the length of the distillation chambers (Figure 4). In order to permit the fitting together of the superposed elements, each of them comprises at one end (upper or lower) a countersunk part or annular recess *b*⁴ and at its other end a corresponding projecting part or annular flange *b*⁵, in the wall around the tubular hollow *b*¹ in the centre.

The tubular cavities *b*¹ of the superposed refractory elements form by their assembly 80 conduits or flues serving for the passage of the flames and combustion gases for the heating of the distillation chambers *a* along their longer sides. In the example illustrated, there are represented three elements *b* along 85 each of the long sides of a distillation chamber (Figures 1 and 2), but it will be understood that this number may vary according to the length of the chamber and the dimensions given to the elements *b* utilized for 90 the construction of the heating piers.

Since continuous distillation retorts require a temperature decreasing rapidly from the bottom upwards, each of the elements *b* of the heating piers (Figures 9 and 10) comprises, internally, on both sides of the major axis of its tubular cavity *b*¹, vertical axial notches *b*⁶ in which are engaged the ends of a refractory brick *b*⁷; the latter thus constitutes an axial partition, arranged parallel 100

to the longitudinal walls of the distillation chamber, in the central cavity b^1 of each element b . The flames and combustion gases are thus caused to strike against these bricks b^1 , which leave only a small free space between them and the walls of the elements b ; there is thus produced an energetic stirring up of the gaseous molecules, which activates the combustion to a large extent; moreover there results a very intimate contact of the hot gases with the walls to be heated, which increases considerably the coefficient of transmission of the heat. The latter is thus given up very actively to the walls and the temperature decreases very rapidly in the inverse direction to the downward movement of the material in the distillation chamber a , thus realizing the most favourable conditions for an economical heating and the best output of by-products.

The heating gas is admitted at the lower part of the flues formed by the superposition of the tubular hollows b^1 of the elements b . The elements b , at the base of the distillation chamber, each comprise in their tubular hollow a brick c (Figures 11 and 12), extending over the whole height of the element; this brick c is formed with an axial hole c^1 which is intended for the passage of the heating gas, while air necessary for the combustion of this gas passes through the lateral channels c^2 formed upon both sides of this brick c , in the tubular hollow or cavity b^1 of the element b .

The elements at the base of the distillation chamber thus constitute, by their superposition, channels c^1 and c^2 for the passage of the gas and air for combustion, respectively (see the left hand half of Figure 1); air is admitted freely at the base of the channels c^2 , while the heating gas is admitted through branch pipes d^1 provided with cocks and leading from the gas supply main d . The two fluids (gas and air), intended for combustion, admitted and circulating separately in the vertical channels c^1 and c^2 at the base of the distillation chamber piers, become heated during their passage through these piers and thus recuperate part of the heat contained in the residue of the distillation of the material, from the lower part of the distillation chambers; the combustion of these fluids (gas and combustion air) commences where the air and combustion gas meet. The flames and gases, after the combination of the air and heating gas, then continue their vertical movement in the heating flues b^1 of the piers.

In the upper part of the heating piers, the temperature of the gases being sufficiently low, the refractory elements b may be replaced by cast iron members e , which carry out the same method of circulation and are fitted in the same manner into the refractory elements b situated below them (Figure 4). These upper cast iron members e are connect-

ed by collectors e^1 , above which there is arranged the smoke flue f for the escape of the burnt gases towards the chimney f^1 .

The distillation gases from the material escape from the distillation chambers a through numerous openings a^1 arranged in any suitable manner over the entire heating height of the retort, in the axial plane of each of the chambers a in the small unheated sides of these chambers; these openings a^1 connect with vertical collecting channels g and discharge into a common main g^1 , with interposition of a valve g^2 , arranged at the upper part of this vertical collector g and allowing of isolating each distillation chamber.

In order to ensure a total recuperation of the heat contained in the residue such as coke, semi-coke or distilled shale of distillation of the material used, at the base of the distillation chambers a , there is effected—in addition to the recuperation by the fluids (gas or air for combustion) circulating at the base of the heating piers in the channels c^1 and c^2 , along the long sides of the distillation chambers, as indicated above—a recuperation of heat by another fluid, gas or steam, which is blown into the distillation chambers a through the small sides of these chambers (Figures 1, 3 and 4).

Producer gas or steam intended to be blown into the chambers a is admitted externally of the distillation chamber into vertical channels constituted by metal trunks h arranged in the transverse direction of the distillation chambers a , between the latter, in the brick-work at the base of the retort. The gas or steam then enters into the distillation chambers a through openings h^1 h^2 formed at the top of these trunks, at different heights, and opening out into the chambers a at the small sides of the latter. When steam is utilized for this recovery of heat, this steam may be made by means of water occupying the base of the vertical channels h .

Each of the distillation chambers a might comprise two distinct vertical channels h for this blowing in of gas or steam, but it is preferable, when several distillation chambers are connected in a battery, as illustrated, to unite the different vertical channels, corresponding to a small face of the different chambers, into a single channel extending transversely over the whole length of the battery (Figures 3 and 4).

When the distillation chambers are arranged in series-parallel, there may be provided a single series of vertical channels arranged in the wall separating the two series of parallel chambers, between the small sides of those chambers.

By the direct contact of the fluid (gas or steam), blown in at the base of the distillation chamber, there is effected, in combination with the external recuperation by the

heating fluids, a sufficiently complete cooling of the residue before its exit from the distillation chamber. The recuperation of heat effected by this arrangement is extremely energetic and rapid and the economy realized is carried to a maximum. In the case of a pulverulent residue, for example with lignite, the blowing in of gas, or steam into the distillation chambers is effected at a sufficient height above the retaining register at the base of the distillation chamber to prevent an external leakage of fluid at the bottom, even during the opening of the register.

As the material is heated more rapidly along the walls of the distillation chamber than in the centre of the latter, there is utilized preferably, at the base of each distillation chamber, an oscillating retaining register; the latter is constituted by a member *i* 15 in the shape of a circular arc at its upper end, blocking the lower end of the distillation chamber, and mounted upon a horizontal spindle *i*¹ so as to be able to oscillate; during this movement of oscillation, in one direction or the other, separating the register from one of the walls of the distillation chamber, the residue of distillation in the region adjacent to this wall descends more rapidly than the material in the central zone of the chamber; 20 during the movement of oscillation of the register *i* in the other direction, it is the material in the zone adjacent to the other wall of the chamber which descends in the first place. Cranks *i*² keyed upon the spindles *i*¹ permit 25 the operation of these registers *i*.

The supply of continuous distillation resorts with pulverulent materials formed from the pulverulent constituents contained in the coal, lignite, or other combustible material to be subjected to distillation, for example, coal dust, presents certain difficulties for maintaining the distillation chamber constantly filled up to its upper part without presenting voids at the supply point. 40 These latter would in effect be harmful to a satisfactory yield of by-products such as tar oils, owing to the decomposition of the latter during their more or less prolonged sojourn in these voids.

Now the arrangement, above the distillation chamber, of a single hopper of fairly great height and of sufficient capacity for ensuring a continuous supply, without any register, presents several disadvantages: (1) 50 in the case of slightly moist pulverulent materials, arches are frequently formed at the base of the hopper which produce blockages and therefore an irregular supply; (2) in the case of a stoppage of the elevating apparatus delivering materials into the hopper, the level of these materials may fall too low and no longer suitably obstruct the upper part of the distillation chamber, in such a way as to prevent any exit of gas or any 55 entrance of air.

In order to obviate these disadvantages, there is utilized, as represented, in combination with the supply hopper *k*, a very simple register constituted by a butterfly flap *l* adapted to turn around a horizontal axis *l*¹; 70 this register is not sufficiently tight to shut off completely by itself alone the distillation chamber *a* at its upper part; but in combination with the supply hopper *k*, filled with pulverulent materials, arranged above this register, there is obtained an absolutely perfect obturation, even if the hopper is only 75 partially filled.

During the normal working of the distillation supply apparatus, when the hopper is suitably filled with pulverulent materials, the register can remain in the vertical open position (Figure 1) and it will suffice to shake it at sufficiently close intervals in order to prevent any blockage at this point. 80 In case of stoppage of the supply apparatus, the register *l* is placed in the horizontal position, this register thus preventing the material from descending and constituting, in combination with the material contained in the hopper, a perfect obturation 85 during the whole duration of the stoppage of the supply apparatus. In order to avoid any movement of the register outside the few short instants of its operation, it is held fast in its normal open position by engaging its operating lever *l*² by any suitable latching device.

What I claim is:

1. In a vertical continuous distillation apparatus, a distillation chamber, the longitudinal walls of which are constituted by tubular elements of refractory material and of prismatic shape, and each of said elements having a single oblong cavity, said elements being superimposed and fitted together in such a manner that the continuous vertical gas tight flues formed by the cavities of the superimposed elements are completely separate each from another and have no communication with the distillation chamber, said vertical flues being adapted to the passage of the gases serving for the heating of the distillation chamber, the provision, along the major axis of the oblong cavity of each of said tubular elements, in the heating zone proper of the apparatus, of a separate brick extending for a small part of the height of the tubular element, and forming a partition parallel to the longitudinal walls of the said oblong cavity, an off-take for the distilled volatile products and of means for carrying said separate brick, for the purpose described.

2. In a vertical continuous distillation furnace, (as claimed in claim 1), the provision, at the ends of the major axis of the oblong cavity of each of said tubular elements in the heating zone proper of the furnace, of internal vertical axial notches, in combina-

tion with a separate brick, adapted to be engaged at its ends in the said axial notches of said element, said brick extending for a small part of the height of the tubular element and forming a partition parallel to the longitudinal walls of the said oblong cavity, for the purpose described.

3. In a vertical continuous distillation apparatus (as claimed in claim 1), the provision of means for the admission of the gas and of the air intended for combustion into the heating piers at the base of the apparatus, and of separate vertical channels formed in the tubular cavities of the superposed tubular elements for the circulation of said gas and of said air of combustion up to a certain height at the lower end of the apparatus piers, for the purpose described.

In testimony whereof I have signed my name to this specification.

JULIEN PIETERS.
